UNITED STATES PATENT OFFICE

97,130

DESIGN FOR A BOILER OR FURNACE JACKET

George D. Hauser, Utica, N. Y., assignor to Crane
Co., Chicago, Ill., a corporation of Illinois

Application March 16, 1935, Serial No. 55,898

Term of patent 14 years

To all whom it may concern:

Be it known that I, George D. Hauser, a citizen of the United States, residing at Utica, in the county of Oneida and the State of New York, whose post office address is % Utica Products Inc., Utica, New York, have invented a new, original, and ornamental Design for a Boiler or Furnace Jacket, of which the following is a specification, reference being had to the accompanying drawing, forming part thereof.

The drawing illustrates a perspective view of the jacket, embodying my design, the door thereof being shown in closed position. The rear of the jacket is plain and the side not shown is identical with the side shown.

I claim:

The ornamental design for a boiler or furnace jacket substantially as shown and described.

GEORGE D. HAUSER.
